UNITED STATES PATENT OFFICE.

THOMAS A COLEMAN, OF VREDENBURGH, ALABAMA, ASSIGNOR TO PETER VREDENBURGH, JR., OF VREDENBURGH, ALABAMA.

FEEDING-ROLLER FOR LATH AND BOLTER MILLS.

1,233,985.

Specification of Letters Patent. Patented July 17, 1917.

Application filed March 25, 1916. Serial No. 86,575.

To all whom it may concern:

Be it known that I, THOMAS A. COLEMAN, a citizen of the United States, residing at the town of Vredenburgh, county of Monroe, and State of Alabama, have invented a certain new and useful Improvement in Feeding-Rollers for Lath and Bolter Mills, of which the following is a full, clear, and exact description, such as will enable others skilled in the art to which it appertains to make and use the same, reference being had to the accompanying drawings, forming part of this specification.

This invention relates to the manufacture of lumber, and specifically to certain improvements in the construction of feeding rollers for bolter and lath mills. As is well known in the art, bolter and lath mills are designed to rip light and narrow stuff, and the function of the feeding rollers in such mills is to feed the material to the action of the saws and hold it straight while it is being cut. Consequently, it is essential that the feeding rollers shall be positive in their operation, both in their operative engagement of the material, and in their feeding movement. In the attainment of this positive operation, it is essential that the peripheral engaging elements be kept sharp so that they will prevent slipping of the material, and that they be replaced when worn, in order that the feeding operation be uniform. Furthermore, it is essential that there be no interruptions in the work engaging portion of the roller along the length of the roller, as such interruptions would permit the narrow material to "ride" the roller, the roller affording no operative means of engagement for feeding the material forward.

In the roller constituting my present invention, it is my object to provide a structure wherein the roller will be provided with engaging elements throughout its entire length, which engaging elements will be operative to feed material through the mill, and the said engaging elements being readily removable from the roller and replaceable, so that the roller may be quickly repaired when any of the elements may be come injured or worn. As a consequence, in

this improved form of roller, the entire work surface may be maintained on the proper radius so as to insure accurate and uniform feeding of the material.

In the accompanying drawings— 55

Figure 1 represents an elevation, broken away in parts, showing an embodiment of my invention;

Fig. 2 is a section substantially on line 2—2 of Fig. 1; 60

Fig. 3 is a fragmentary perspective of one end of one of the carriers.

Referring to said drawings in detail, it will be understood that 1 is a shaft, which may have its terminal portions turned down 65 to form journals, whereby the shaft is adapted to be mounted in suitable bearings in the machine. 2 is a clamping collar which is keyed, shrunk, or otherwise secured on the shaft. 4 is the seat portion of the 70 shaft upon which the movable portions of the roller are carried, with the exception of the movable clamping collar 5 which is screw-seated on a thread 6 turned in the shaft at the end of the seat portion opposite the 75 clamping collar 2.

Upon the seat portion are disposed carriers 7 which are in the form of cylindrical drum members having the bearing portions 7^a which rest upon the seat portion 4. 80 There is no direct connection between the carriers 7 and the shaft, so that the former may be moved both longitudinally and circumferentially on the shaft. The carriers are provided with longitudinal slots 7^b, extending radially into the carriers, and continuously from end to end thereof. The carriers are also provided with annular grooves 7^c which are deeper than the longitudinal grooves 7^b, and which intersect them. 85 The ends of the carriers are formed with the undercut portions 7^d having a female bevel, and the clamping collars have similar annular undercut portions 8.

A plurality of identical tooth bars 9, 95 which form the engaging elements of the roller, are provided, the width of said bars being such as to permit them to fit snugly in the longitudinal grooves 7^b and their length being somewhat in excess of the 100

length of the carriers 7. The operating margins of these tooth bars may be serrated or otherwise formed to engage the material in such fashion as to permit of a positive operation. The ends of the bars are shaped with sloping edges which diverge from the operating margin of the bar, the said sloping edges being cut on the same angle relative to the inner margin of the bar as are 5 the undercut portions 7^a and 8 relative to the shaft. One end of each bar is formed with an extension 9^b extending from the inner terminus of the sloping edge. The 10 length of these extensions is sufficient to 15 extend across the periphery of the undercut portions 8 of the clamping collars.

In assembling the roller, the carriers are placed upon the seat portion, and the tooth bars are placed in the slots 7^b, the disposal 20 of the carriers being such that the slots and bars on one are staggered or offset relative to the slots and bars on the other. The clamping collar 5 is then tightened up by means of a spanner, so that it engages the 25 tooth bars on the adjacent carrier, the extensions 9^b extending across the periphery of the undercut portions 8, and the sloping edges of the bars being engaged under the undercut portion 8. As the clamping collar 30 is tightened up the adjacent carrier and the tooth bars thereon will be moved toward the other carrier, until the carriers respectively engage the projecting ends of the tooth bars on the adjacent carrier, the sloping ends of 35 the tooth bars of the respective carriers being projected under and engaged by the undercut portion 7^a of the other carrier. The extremities of the tooth bars on the carrier adjacent the clamping collar 2 will 40 be engaged by the undercut portion 8 as above described with reference to the movable clamping collar. Thus it will be seen that by tightening up the clamping collar 5, pressure is transmitted through the engaging 45 elements 9 on the carrier adjacent the movable clamping collar to the other carrier, and pressure is exerted through the carrier adjacent the movable clamping collar upon the engaging elements mounted in the 50 other carrier. Due to the beveled form of the interengaging portions of the clamping collars, carriers and tooth bars, the latter will be cammed into their seats by this pressure exerted between the clamping collars, 55 anchoring them firmly in position, and the carriers will be jammed so that they will be held for rotation with the shaft. In this condition the roller is ready for operation, and it will be seen that there are no intervals 60 along its length which are bare of engaging elements about the periphery of the roller. Hence there is no point along the length of the roller at which a narrow piece of stuff will have the opportunity of riding the

roller. As a consequence, the roller will feed 65 uniformly throughout its length.

In the event that it becomes desirable to replace any of the tooth bars, such may be done with very little effort and in a very short space of time, by simply slackening up 70 the clamping collar 5 sufficiently to permit the adjacent carrier being moved away from the other carrier to an extent sufficient to clear the ends of the engaging elements. Then the engaging elements may be removed 75 from their seats, and replaced with new ones. In case any of them become stuck or rusted in their seats, as frequently occurs in handling wet material, particularly if it is wet with salt water, the removal is easily 80 accomplished by inserting a tool, such as the end of a file or similar implement, through one of the peripheral slots 7^c and underneath the inner edge of the bar, whereupon the bar may be readily pried out. 85

It will be understood, of course, that in the practical embodiment of the invention, the roller will be provided with a considerably larger number of slots and tooth bars than is illustrated in the accompanying drawings, 90 many of the same having been omitted in the accompanying drawings for the purpose of clearness.

It is also to be observed that the invention is not limited to the specific form herein illustrated and described, but that it comprehends all obvious and expedient modifications or altered forms within the scope of the invention as indicated in the following claims. 100

What I claim is:

1. A feeding roller for lumber machines comprising a shaft, carriers mounted thereon and being relatively movable, said carriers being provided with longitudinally extending peripheral slots, engaging elements seated in said slots and extending beyond the ends of the carriers, the respective carriers having ends formed to engage the extremities of engaging elements on the other carrier, and terminal clamping means adapted to coöperate with the carriers and the engaging elements to clamp the latter in their slots. 105

2. In a feeding roller, the combination of a shaft, carriers longitudinally movable thereon, said carriers being provided with peripheral longitudinally extending slots and having annular undercut portions at their ends, engaging elements seated in the longitudinal slots in each carrier and having their extremities formed to engage under the undercut portion of the other carrier, and terminal clamping members for holding the carriers and engaging elements in contact to retain the latter in the slots. 110 120 125

3. In a feeding roller, the combination of revolvable carriers mounted for relative

movement toward and from each other, work engaging bars removably mounted on each carrier and spaced apart about its periphery, the bars on a carrier having engagement at their extremities with the other carrier whereby they are retained against displacement.

In testimony whereof I hereunto affix my signature in the presence of two witnesses, this 21st day of March, 1916.

THOMAS A. COLEMAN.
